APPARATUS AND PROCESS FOR PRODUCTION OF PULP

Application filed January 27, 1928. Serial No. 249,845.

The present invention relates to processes for cooking wood and other cellulosic material for the formation of pulp, and it has particular reference to the preliminary operations in the sulphite process, to the relief of the digester, to the utilization of the heat in the materials relieved, to the recovery of the materials, and to the combination of such utilization and recovery with said preliminary operations.

In the cooking of wood by the sulphite process, using any of the suitable bases, of which calcium, magnesium and sodium are commonly known, it is necessary to use an acid sulphite and an excess of free sulphurous acid dissolved in the cooking liquor. The excess acid usually varies in amount. It is not constant, because it is held very loosely in the liquor, and increased heat and decreased pressure both cause it to be discharged from solution in the liquor. It is therefore customary to charge a digester with a cooking liquor in which the free acid content is very high. The tendency of the subsequent heating to drive it off is somewhat balanced by the tendency of the increasing pressure to prevent its escape. In the present practice of the sulphite process where steam is injected into the liquor there is an escape of much free acid from the process, and this is accompanied by discharge of a quantity of the cooking liquor. Vents or relief lines suitably placed about the digester have valved controls to regulate the escape of such material and to control the pressure.

It is quite desirable to have all the chips in the digester covered with the cooking liquor, and accordingly the digester is quite full. The injection of the heating steam causes condensation, and in order to accommodate the increased volume of water resulting from such condensation a portion of the liquor is released. It is customary to bleed liquor from the digester at a rate which will compensate for the water being added. This

liquor and the acid which is also set free are greatest in amount at the beginning of the heating operation and in the early part of the cook, but nevertheless a substantial amount of gas and vapor escape during all 50 the cook. The material first removed by relief is of greater purity than that which is later relieved, for after the cooking has proceeded there are present in the liquor various impurities removed from the chips, such as 55 pitch, lignins, dissolved resins, oils, organic acids, etc.

In the preliminary operations of the sulphite process the liquor is usually introduced so that heating begins at a temperature of 60 about 70° C., and cooking action does not begin until three or four hours after the heating commences. This heating period involves the introduction of much water as steam, and requires the displacement of an 65 equivalent amount of liquor, with the disadvantage that the original liquor is diluted. Much of the cooking value in the liquor both as dissolved solids and as free acid, is thus lost through the relief system before 70 any cooking takes place, and the loss continues as cooking occurs. Much heat is carried away from the digester during the relief.

Various processes have been proposed for 75 conserving the chemical value and the heat of the relieved materials, such, for example, as the introduction of them into liquor being prepared for a subsequent cooking operation. Absorption of the free acid gas 80 at atmospheric and at greater pressures has been proposed, but there are disadvantages to these operations. At atmospheric pressure the temperature which can be attained is limited. At higher pressures the back 85 pressure increases and a constant and uniform relief cannot be maintained. Furthermore, the introduction of the relief materials into the new liquors contaminates them with the impurities which they carry, and there

is thus an accumulation of detrimental materials which gives low grade pulp in subsequent cooking operations with such liquor.

The present invention aims to use the relief materials for preheating and for enriching raw liquors, so that a substantial part of the heat is recovered, all the free acid utilized, a substantial part of the high quality cooking chemicals of the relief conserved, 10 and the low grade contaminated relieved chemicals kept away from the raw liquor and otherwise disposed of.

The practice of the present invention produces a high grade cooking liquor which is rich in sulphurous acid, which is heated to a temperature much over 100° C., and which can be discharged into the digester at such temperature onto the chips under a pressure sufficient to conserve its heat and its acid content. The use of hotter charging liquors than is normally practiced decreases the amount of steam that is required to heat the charge to cooking temperature, decreases the resultant dilution, and thereby increases the heat and the chemical efficiency of the process. In addition to all these advantages the time of operation is reduced, first, by cutting off a considerable period of preliminary heating, and second, by cutting down the cooking time as a result of the stronger liquor retained during the cooking period. An improved and more uniform pulp is obtained by reason of the more rapid impregnation of the chips by the hotter and stronger liquor prior to the cooking stage, and the more rapid and uniform cooking of the more thoroughly impregnated chips.

Various other advantages of the present invention will be apparent from the following description of the process and the apparatus which is hereinafter given as an example of the invention as it is applied specifically to the sulphite process using a calcium base, and as shown in the accompanying drawing.

In the drawing there is shown a digester, a separator and an accumulator, with various connections for suitable operation of the process.

50 In order to explain the invention and to enable others to comprehend the scope of the appended claims a detailed reference to the apparatus and to its operation is given. A digester 10, as commonly used for the sulphite process, being roughly fifty feet in height and about fifteen feet in diameter, is arranged to be charged with chips from a supply 11 through a removable top 12. The bottom of the digester is fitted with connections for a blow line 13, a steam injection line 14, and a liquor supply line 15. Such connections may of course be otherwise made without in any way departing from the present invention. Suitable valves are provided 60 in these lines, for example, 16 in the blow

line, 17 in the steam line, and 18 in the liquor supply line. Various relief lines, as generally employed in the art, are connected to the digester, in the present instance line 19 with valve 20 being located near the top 70 for the relief of gas and vapor, and line 21 with valve 22 being located lower on the side of the digester for relief of liquor.

The two relief lines unite beyond their valves into line 23 leading into a separator 75 for the separation of liquid and gas and/or vapor. In the present instance a horizontal cylindrical tank about eight feet long by two feet in diameter is designated 24, with line 23 entering one end at the center. The bottom of the tank is connected for drainage to a line 25 with valve 26. This drainage line may lead to a waste receiver or to the usual liquor cooler used for sulphiting apparatus, or to any other means for disposal 80 of the separator liquor. Liquid, or gas and vapor which may collect above a liquid level in the separator, is conducted through line 27 to suitable means which will utilize the chemical and heat value in accordance with 85 the present invention.

The present invention provides what is hereinafter termed an accumulator. This has a multiplicity of functions, all of which will be clear from the following description of its construction, its connections, and its operation. In general, it serves as an absorbing chamber for the free acid of the relief and as a receiver for some of the relieved cooking liquor. It serves also as a heat exchanger to absorb heat from material flowing out of the separator discharge line 27. More specifically, it serves as a saturator for adding free sulphurous acid to raw liquor for a succeeding or for another cooking operation, as a preheating pressure chamber for raw liquor, and also as a pressure blow case for filling the cooking digester. In the present instance it may serve as a gravity feed supply for digester 10.

The accumulator is preferably provided as a pressure tank 28 of steel, and it is lined as indicated at 29 to render it acid resistant. It has a valved vent 30 at the top, a liquid level gauge 31, and a bottom drain or discharge line 32 with control valve 33. In size it is preferably sufficiently large to hold a full charge of liquor for digester 10, but it may be smaller and other raw liquor to the amount required may be drawn from the ordinary sources of supply. An old digester is suitable as an accumulator, but when special installations are employed it is desirable to have the accumulator elevated in order to utilize a gravity feed to the digester 10. The drain line 32 serves also as a supply line to the accumulator. This line 32 is connected to a pump 34 through valve 35, and also connected to the feed line 15 for digester 10.

The pump receives raw liquor from a suitable supply through line 36. The accumulator is so connected to the separator discharge line 27 that the relief material in the line may be discharged into the accumulator or may be passed through the accumulator without admixture as through coil 37. The coil is made of acid resistant material such as copper or lead. The preheating coil may be cut off by the valve 38 leading to one branch of a Y-connection 39 mounted on the end of line 27, the other branch being connected into the accumulator by line 40 with valve 41 for discharge at the open end 42. Line 27 may thus be connected alternately or concurrently for discharge into the accumulator and through the coil. Coil 37 emerges from the accumulator as pipe 43. A valve 44 may be placed in the line 43 in order to insure that the gas and vapor in the coil through the accumulator has a sustained pressure to maintain its temperature for proper preheating of the raw liquor in the accumulator. A sufficient length of line 43 may make such valve unnecessary. Usually sufficient length is to be found when the line leads to the cooler which is used in connection with the usual sulphiting towers, to which cooler it is indicated as being connected for saving the sulphurous acid. In order to cut out the coil when desired, a by-pass line 45 with valve 46 is employed. Valves 44 and 38 are thus useful in cutting out the coil at both ends, yet permitting discharge into the accumulator through pipe 40. It is to be understood that suitable acid resistance is provided throughout and further, that insulation against loss of heat will improve the heat recovery and benefit the process.

In the normal operation of the sulphite process liquor at about 70° C. is introduced into the digester to cover the chips. The liquor is strong in calcium bisulphite and free sulphurous acid. Steam is introduced and heating commences. The pressure rises gradually over a period of about three hours to about 70 pounds gauge pressure. The temperature increases at the same time to about 120° C. during which period it is necessary to bleed the digester through line 21 to accommodate the condensed steam. Gas is also relieved, preferably through line 19. This gas at first contains considerable air from the chips and a quantity of sulphurous acid released by the heat. The relief materials are valuable cooking agents (except the air) which are not contaminated, because no cooking has commenced. They pass through the separator and are permitted to flow directly into the accumulator via line 40. Considerable bleeding thus takes place prior to cooking, the separator perhaps emptying itself of liquid several times. Relief is continued after cooking has started—a period of about

three and one-half to four hours after heating begins. When the digester attains a cooking temperature at about 140° C. the liquid bleeding decreases because the condensation is less, but the gas loss continues, and gas and vapor are released continuously from the digester. Cooking continues under these conditions for a period of from three to seven hours or more, according to particular mill practice.

During the first part of the bleeding and the release of gas, the coil line through accumulator 28 is closed at valve 38. The raw liquor in the accumulator is thus heated and enriched by admixture with the free acid gas of the relief and the relieved cooking liquor. Pressure will gradually be built up in the accumulator, to such an extent that the pressure reacts to retard relief. Relief cannot be maintained uniformly as desired under these conditions. The discharge is therefore shifted so that it passes through the coil 37 and thereby gives up its heat. The shift is also made dependent upon the character of the discharge. When cooking has proceeded to such a stage that the impurities in the relief may contaminate the raw liquor, either because of their character or because of their amount, the coil is used to carry off the relief, thereby utilizing the heat of the relief materials without the necessity of mixing the materials with the liquor in the accumulator. The gas passes on through the coil to the cooler and thence to the reaction towers for complete utilization.

By operation as described the charge in the accumulator may be heated up to about 135° C. at a corresponding pressure. When the digester 10 has been emptied of its cook, it is filled with chips from the supply 11, the top 12 is sealed, and the digester is vented, preferably through the separator and the by-pass 45. Valve 35 is closed and valves 18 and 33 opened, so that the pressure behind the pre-heated supply in the accumulator forces it into the digester. The chips cool the liquor to about 120° C. which temperature corresponds to the temperature of the normal cook (beginning at 70° C.) at the end of the first two hours. Thus, the accumulator permits reduction of the preheating time by two hours, prevents decreasing the strength of the liquor by the bleeding and dilution that is eliminated by cutting off the two-hour period of preheating, and permits a shortening of the cooking operation because of the increased strength of liquor and the increased acidity.

In case the accumulator charge is too small for one cooking operation, the additional liquor required is preferably supplied to the digester containing the chips prior to the admittance of the pressure charge.

Several features of the process should be emphasized. All the relief gas is utilized

chemically in the preparation of raw liquor and little of the heat is wasted. No fumes are discharged. The hot cooking liquor is discharged under pressure into the digester, 5 by gravity, by its own pressure, or by both, without the use of pumps. It has heretofore been difficult to charge such liquors when hot into a digester by means of pumps because of the corrosive action on the pumps and the 10 packing. At the first part of the operations clean gas and liquor may be discharged into the accumulator to save the material and the heat content. This should not be continued throughout the cook, because the back 15 pressure prevents proper relief, and because the relief material becomes contaminated with impurities removed from the wood. Admixture of relief with cooking liquor is made prior to the cook, may be made during 20 the first part of the cooking stage, and preferably never during the last part of the cooking stage. The shift of valves so that the material passes through the accumulator coil rather than into the accumulator, serves not 25 only to conserve and to utilize the heat, but it also permits maintaining a uniform rate of relief. This permits of the proper control of the cooking operation. During the latter period of operation the liquor bled 30 from the digester is much less in quantity, and the separator 24 serves to retain it and to separate it from the gas and vapor relief. The separator thus holds many of the impurities in the discharge for subsequent disposal.

The pulp from the shortened process is improved—in part due to the rapid penetration of the chips by the hotter and stronger liquor, and in part due to the quicker action 40 of the stronger liquor in the impregnated chips. Overcooking of the outer part of the chips is reduced, and the pulp is characterized by a freedom of the mass from knots and undercooked portions.

45 It is to be understood that there may be several digesters connected with one accumulator, and that a battery of digesters and of accumulators may be interconnected for selective operation. The example herein given 50 is not to be considered as a limitation of the invention to the apparatus and the process specifically described and disclosed, as it is contemplated that various departures and modifications may be made falling within the 55 scope of the invention as expressed in the appended claims.

It is further to be understood that the process is not limited to the enriching of liquor for the sulphite cooking operation as described. Other liquors which are benefited by addition of material contained in the relief are contemplated, such for example as the enriching of any sodium sulphite liquor by the sulphurous acid relieved from the digester, or by the liquid bled from any process

using a soda base. Preferably, however, the liquor to be preheated is that which is to be used in the next cooking operation. Accordingly, in the appended claims where the term "liquor" is employed it is to be given its 70 broadest meaning.

We claim:

1. The method of treating cooking liquors for the sulphite process of making pulp which comprises relieving a sulphite digester during its operation, discharging the relief materials under pressure into a confined volume of liquor subsequently cutting off said discharge, continuing relief of the digester, and transferring heat from the relief material to said volume of liquor. 75

2. The method of treating liquor which comprises relieving a sulphite digester during its operation, discharging the relief material under pressure into a confined volume of liquor, subsequently cutting off said discharge when the back pressure interferes with the relief of the digester, and continuing relief of the digester. 80

3. The method of treating liquor which comprises relieving a sulphite digester during its operation, discharging the relief material under pressure into a confined volume of liquor, subsequently cutting off said discharge when a predetermined injurious amount of impurities from the cooking digester are present in the relief materials, and continuing relief of the digester. 90

4. The method of recovering relief material from a sulphite digester which comprises relieving the digester, discharging the material removed by relief prior to the start of cooking stages into a supply of liquor, and utilizing the heat in the material removed by relief during the cooking stage by transfer methods. 100

5. The method of recovering relief material from a sulphite digester which comprises relieving the digester, discharging the material removed by relief prior to the cooking stage into a supply of sulphite cooking liquor, and utilizing the heat in the material relieved during the cooking stage by transfer methods to heat said sulphite cooking liquor. 110

6. The method of recovering relief material from a sulphite digester which comprises relieving the digester, discharging the relief material into a supply of raw sulphite cooking liquor, cutting off said supply, separating liquid from gas and vapor of the relief material, transferring the heat from the gas and vapor to said liquor, and subsequently using the liquor for a sulphite cooking operation. 120

7. An apparatus of the character described, comprising a digester, an accumulator, means for discharging relief fluids from the digester into a supply of raw cooking liquor in the accumulator, a separator interposed in the last mentioned means for separating relief 125

liquid from relief gas and vapors, a heat exchanger in the accumulator and communicating with said means, valves interposed in said means for cutting off the discharge of the relief fluids into the accumulator or into said heat exchanger, and a valved conduit for conveying preheated and preconditioned liquor from the accumulator to the digester.

In witness whereof we have hereunto affixed
10 our signatures.
